BRAKE SHOE FOR TYPESETTING MACHINES

Robert J. Lloyd, Detroit, Mich.

Application May 16, 1938, Serial No. 208,271

9 Claims. (Cl. 199—30)

The present invention relates generally to an improvement in typesetting machines and particularly to a brake mechanism for restraining the movement of the assembler rail while a line of matrices are being assembled in the assembler box.

An object of the present invention is the provision of a brake shoe that will not lose its bite on the assembler rail.

10 A still further object of the present invention is the provision of brake shoes that will prevent looseness in the line of mats being formed and thus eliminate V-shaped openings and transposition of words, and space bands.

15 A still further object of the present invention is the provision of a rotatable means in the top or upper shoe, and a detachably secured means in the lower shoe, the said means adapted for engagement with the assembler rail.

20 Other objects of the invention will be more fully understood from the following description and claims when the same are read in connection with the drawing accompanying and forming part of this specification in which:—

25 Figure 1 is a fragmentary front elevational view of the assembling mechanism of a typesetting machine and illustrating the improved brake shoes in gripping position.

Figure 2 is an end elevational view of the brake 30 lever per se upon which the detachable shoes are mounted, the assembler rail being shown in cross section.

Figure 3 is a side elevational view per se of the upper brake shoe and illustrating the rotatable ball mounted bearing at the extreme left hand end.

Figure 4 is a bottom view of the upper shoe and illustrating the position therein of the rotatable bearing.

40 Figure 5 is a side elevational view of the lower brake shoe and illustrating the fixed ball bearing at the extreme right end, the vertical dotted line representing a punch bore.

Figure 6 is a top plan view of the lower shoe 45 and illustrating the position therein of the fixed bearing, the dotted line indicating the position of the punch bore.

Figure 7 is an enlarged detail view of the lever carrying the shoes and illustrating the shoes gripping the assembler rail, parts being shown fragmentarily.

50 Figure 8 is an enlarged detail view of the lever carrying the shoes and illustrating the shoes out 55 of contact with the assembler rail for the return

of the assembler rail to its normal position, parts being shown fragmentarily.

Referring to the drawing, the numeral 9 represents the frame of a typesetting machine to which the assembler rail mechanism is secured. 5 The numeral 10 represents the casing for the matrice chutes, 11 the assembler rail and 12 the reciprocating mechanism therefor.

Pivottally mounted at 13 on the frame 9 is a brake 14 that comprises a lever 15, the lower 10 portion of which is provided with ears 16 and 17. My novel improved brake, comprises an upper shoe 18 and a lower shoe 19. The upper shoe 18 is provided with a bore 20 into which is mounted for rotatable movement a ball 21, the 15 bore 20 being slightly in excess of the diameter of the ball 21. To the right of the midway point, the shoe 18 is provided with a through transverse bore 22 that receives a threaded member 23, the threaded member engaging a threaded bore 24 in the lever 15, detachably securing the shoe 18 to the lever. It is to be noted that the top face of the shoe 18 impinges the lower face of the ear 16. The lower shoe 19 is provided with a bore 25 into which is detachably 25 secured a ball 26. Centrally of the bore 25 is a bore 27 and this bore serves as a means for punching out the ball 26 for replacement or turning the ball over to replace a worn spot on the spherical face of the ball. The provision 30 of a ball provides a gripping means that may be used for an indefinite time due to the fact that only a small area of the spherical surface engages the rail. To the left of the midway point, the shoe 19 is provided with a transverse bore 28 35 which receives a threaded member 29, the threaded member 29 engaging a threaded bore 30 in the lever 15, detachably securing the shoe 19 to the lever. The bottom face of the shoe 19 rests on the upper face of the ear 17. In view 40 of the differences in construction of the two shoes as recited, the upper shoe 18 is marked with the letter U and the lower shoe 19 with the letter L to insure the proper positioning of the shoes on the lever 15.

45 As illustrated in the drawing, Figures 1, 7, and 8, the shoes are assembled on the brake lever 15, the balls disposed diagonally and due to this positioning of the balls a more positive gripping of the assembler rail is effected. The provision 50 of the balls, provides a gripping means in which only a small spherical portion of the balls engage the edges of the assembler rail, thus insuring a tighter grip than the flat edge brake shoes commonly used.

The description about to be made of the operation of the brake involves mechanism well known in the art and it is deemed unnecessary to give same in minute detail, therefore a general description is deemed sufficient. In the operation of my improved brake shoes, as the star wheel (not shown) deposits the matrices on the assembler rail, the assembler rail 11 is moved to the left against the tension of a spring (not shown) that 5 is connected to an arm 31' on the lever 31, the spring tension acting against the assembler rail through the intermediate pivoted lever 31 having its lower end 33 connected to one end of a link 34, the other end of the link 34 connected at 35 10 to the assembler rail 11. As the assembler rail 11 is moved to the left during the composition of a line, it is held in its displaced position by the brake 14 that comprises the lever 15, the lower end of which carries the upper shoe 18 in which 15 is mounted the rotatable bearing 21 that engages the upper edge of the assembler rail 11 and the lower shoe 19 having the fixed bearing 26 that engages the lower edge of the assembler rail as 20 illustrated in the enlarged detail view of Figure 25 7 of the drawing. The brake shoes 18 and 19 are held in contact with the assembler rail 11 by the spring 36, one end pulling on the brake lever 15, one end of the spring being secured to the 30 brake lever 15 and the other end secured to the bracket 37 on the frame. When the composed line is transferred to an assembling elevator (not shown) means well known in the art release the 35 brake 14, the brake lever assuming the position illustrated in Figure 8 of the drawing and allowing the assembler rail and its associated mechanism to return to its normal position. It is to be noted in Figure 8, that in the return position the balls do not engage the assembler rail.

My improved brake shoes are adapted for use 40 on typesetting machines, such as the Intertype and Linotype machines and require no change of mechanism, simply remove screw in the old type of shoes and replace the old shoes with my improved ball grip shoes.

Changes in detail may be made without departing from the scope of the claims hereto appended.

What I claim is:—

1. A brake for assembler rails of typesetting machines, comprising a lever, shoes detachably secured to said lever and spherical means mounted in said shoes adapted to bear on the top and bottom edges of said rail.
2. A brake for assembler rails of typesetting machines, comprising a lever, shoes detachably secured to said lever, spherical means mounted in said shoes opposite the top and bottom surfaces of the rail, said spherical means disposed at an angle to each other.
3. A brake for assembler rails of typesetting machines, comprising a lever, shoes detachably secured to said lever, spherical means mounted

in said shoes, one of said shoes provided with spherical removal means, said spherical means disposed at an angle to each other and adapted to bear on the top and bottom edges of said rail.

4. A brake for assembler rails of linotype machines comprising an upper shoe and a lower shoe, gripping means mounted in said shoes bearing on the top and bottom surfaces of the rail, the gripping means in the upper shoe loosely mounted for rotative movement, the gripping 10 means in the lower shoe fixedly mounted therein, said lower shoe provided with a punch bore for permitting insertion of removing means for said gripping means.

5. A brake for assembler rails of linotype machines comprising an upper shoe and a lower shoe, spherical means mounted in each of said shoes, a portion of said spheres adapted for engagement with the edges of said assembler rails, and means in the lower shoe for permitting insertion of re- 20 moving means for said spherical means.

6. A brake for assembler rails of typesetting machines comprising a lever, an upper shoe and a lower shoe, spherical means mounted in said shoes adapted to bear on the top and bottom 25 edges of the rail, the spherical means in the upper shoe loosely mounted for rotative movement, the spherical means in the lower shoe fixedly mounted therein, said shoes detachably secured to said lever and a punch bore in said lower 30 shoe for permitting insertion of removing means for said spherical means.

7. A brake for assembler rails of linotype machines comprising an upper shoe and a lower shoe, spherical means mounted in each of said shoes 35 a portion of said spherical means adapted for engagement with the edges of said rails said spherical means disposed in different vertical planes, a portion of the periphery of said spheres adapted for engagement with the edges of said assembler 40 rails, the lower shoe provided with a punch bore for permitting insertion of removing means for said spherical means.

8. A brake for assembler rails of typographical machines, comprising a lever, shoes detachably 45 secured to said lever, spherical means mounted in said shoes for engagement with the top and bottom edges of said rail, one of said spherical means loosely mounted for rotative movement, the other of said spherical means fixedly and detachably secured therein.

9. A brake for assembler rails of typesetting machines, comprising an upper shoe and a lower shoe, a ball mounted in each of said shoes for engagement with the top and bottom edges of 55 said rail, the ball in the upper shoe loosely mounted for rotative movement, the ball in the lower shoe fixedly secured therein, the lower shoe provided with a means for insertion of ball removing means.

ROBERT J. LLOYD.
